US00D999532S

(12) **United States Design Patent** (10) **Patent No.:** **US D999,532 S**
(45) **Date of Patent:** **** Sep. 26, 2023**

(54) **SKIN CLEANSING APPARATUS**

(71) Applicant: **LG ELECTRONICS INC.**, Seoul (KR)

(72) Inventors: **Gayeong Lee**, Seoul (KR); **Minji Seo**, Seoul (KR)

(73) Assignee: **LG ELECTRONICS INC.**, Seoul (KR)

(**) Term: **15 Years**

(21) Appl. No.: **29/801,902**

(22) Filed: **Aug. 2, 2021**

(30) **Foreign Application Priority Data**

Feb. 19, 2021 (KR) 30-2021-0008574

(51) **LOC (14) Cl.** **04-02**

(52) **U.S. Cl.**

USPC **D4/100**; D24/215

(57) **CLAIM**

The ornamental design for a skin cleansing apparatus, as shown and described.

DESCRIPTION

FIG. 1 is a front, right side perspective view of a skin cleansing apparatus showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is another perspective view, shown in an environment of use.

The broken lines shown in the drawings depict portions of the article and form no part of the claimed design. The broken lines shown in FIG. 8 depict environmental subject matter and form no part of the claimed design.

1 Claim, 8 Drawing Sheets
